UNITED STATES PATENT OFFICE.

JOSEPH SOSS AND LOUIS H. MORIN, OF NEW YORK, N. Y., ASSIGNEES TO SOSS MANUFACTURING CO., OF BROOKLYN, NEW YORK, A CORPORATION OF MAINE.

DIE-CASTING MACHINE.

Application filed February 18, 1922. Serial No. 537,419.

To all whom it may concern:

Be it known that we, JOSEPH SOSS and LOUIS H. MORIN, citizens of the United States, and residing at New York, in the county of New York and State of New York, have invented certain new and useful Improvements in Die-Casting Machines, of which the following is a specification, such as will enable those skilled in the art to 10 which it appertains to make and use the same.

This invention relates to die-casting machines, or machines designed for use in the manufacture of die-cast products of various 15 kinds and classes, and the object of our invention is to provide a machine of this class which is automatic in operation, that is to say, the operative parts of our machine are automatically and mechanically moved into 20 their several positions in the formation of die-castings; a further object being to provide means for controlling the operation of the machine; a still further object being to provide means for holding and locking the 25 dies or die holders of the machine in their operative position; and a still further object being to provide automatically operated means for passing molten metal into the die or dies supported in the machine; and with 30 these and other objects in view the invention consists in a machine of the class and for the purpose specified which is simple in construction and operation and efficient in use, and which is constructed and operated 35 as hereinafter described and claimed.

The invention is fully disclosed in the following specification, of which the accompanying drawings form a part, in which the separate parts of our improvement are designated by suitable reference characters in 40 each of the views, and in which:—

Fig. 1 is a side view of the complete machine and showing the parts thereof in a normal or inoperative position;

Fig. 2 a view similar to Fig. 1 but showing only a part of the construction and on an enlarged scale;

Fig. 3 a plan view of the construction shown in Fig. 2;

Fig. 4 a view similar to Fig. 1 but showing another part of the machine on an enlarged scale;

Fig. 5 a plan view of the construction shown in Fig. 4;

Fig. 6 a partial section on the line 6—6 of 55 Fig. 5 with parts of the construction shown in different positions;

Fig. 7 a view similar to Fig. 6 with parts of the construction shown in different positions and indicating the method of passing 60 molten metal into a die mounted in the machine;

Fig. 8 an end view of the machine as shown in Fig. 2 of the drawing;

Fig. 9 a diagrammatic sectional view 65 showing the operation of the clutch mechanism of the machine;

Fig. 9^a a sectional detail view of a part of the clutch mechanism which is not shown in Fig. 9;

Fig. 9^b a detail view of a part of the construction shown in Fig. 9;

Fig. 10 a transverse sectional view through an air valve employed in the construction shown in Figs. 1 and 4 of the drawing and 75 showing the same in an operative position;

Figs. 11, 12 and 13 are diagrammatic detail views of die supporting or holding operating mechanisms and showing the several operative positions thereof;

Fig. 14 a diagrammatic view of the air valve operating mechanism which we employ;

Figs. 15 and 16 diagrammatic detail views of the supplemental frame operating mechanism of the machine which we employ and showing the different positions thereof; and,

Fig. 17 a view showing perspectives of a number of links, levers, couplings and the like which we employ.

Heretofore it has been the custom to provide die casting machines of the class and for the purpose specified with means adapted to be manually operated for moving the various parts of the machine, as for example, the die-holders and carriers and the like into operative and inoperative positions, which requires the use of considerable strength on the part of the operators, and is very tiring as well as being slow, and it has also been the custom to employ two or more men for operating a single machine, and the principal object of our present machine is to eliminate all manual labor in the operation of machines of this class and to provide a machine, the operation of which is started through a suitable clutch mechanism or the like, after which the machine, or the vari-

ous parts thereof, are automatically operated to perform the several functions of the machine in the production of die-castings.

In the accompanying drawings, we have shown one method of carrying our invention into effect in which 20 represents the main or base frame of the machine mounted upon legs 21, and on top of the main frame 20 are tracks or rails 22 which extend longitudinally thereof and upon which is movably mounted a supplemental frame 23 provided with rollers or wheels 24 movable over the tracks or rails 22.

Mounted in suitable bearings in the supplemental frame 23 is a cam shaft 25 upon which is mounted two cams 26 provided in the periphery thereof with gear teeth to form gears of said cams, and mounted upon the shaft 25 between the cams 26 are other cams 27 provided in the periphery thereof with gear teeth to form gears thereof. The cams or gears 26 and 27 are adapted to mesh with pinions 28 on an intermediate shaft 29 mounted in the supplemental frame 23.

Secured to the shaft 29 is a gear 30 which is located centrally of and between the gears 27 and is adapted to mesh with a pinion 31 mounted upon a drive shaft 32 of the machine. A pulley 33 is mounted upon one end of said drive shaft, and said shaft is mounted in suitable bearings 34 on the supplemental frame 23.

A suitable clutch mechanism 35 is mounted upon the drive shaft 32 and is operated by a yoke 36 adapted to engage the groove of the clutch 35, as clearly shown in Fig. 9^a of the drawing, and the yoke is pivoted as shown at 37 to which pivot is connected a clutch operating handle 38 through a connecting rod 39, which has a universal joint connection with the pivot 37 as shown at 40. The movement of the handle 38 will cause the clutch 35 to engage the gear 31, causing the rotation of said gear and the gear 30 on the shaft 29 which will correspondingly rotate the pinions on said shaft and the cams or gears 26 and 27.

On the cam shaft 25 is mounted a cam 41 provided with a recess 42 in the periphery thereof, and a roller 43 is adapted to operate in connection with the cam 41 or the recess 42 thereof, said roller being carried by a plunger 44 supported in the supplemental frame as shown at 45 and 46, and the roller 43 is normally held in engagement with the cam 41 by a bell crank 47, and a spiral spring 48, the bell crank 47 being placed in operative connection with the yoke 36 by a connecting rod 48, as clearly shown in Fig. 9 of the drawing, and this mechanism provides means for automatically moving the clutch 35 into an inoperative position on the completion of one revolution of the cams or gears 26 and 27, or the completion of one cycle of operation

of the machine. An adjusting nut 49 is mounted upon the rod 46 to regulate the tension of the spring 48.

The cams 26 are provided on their faces with cam grooves 50 in connection with which anti-friction rollers 51 carried by, or mounted upon, levers 52 operate, said levers being provided with elongated apertures 53 through which the shaft 25 passes, and the ends of said levers are pivoted to bell cranks 54 as shown at 55, said bell cranks being pivoted as shown at 56, and other bell cranks 57 pivoted at 57^a are connected with the bell cranks 54 by a connecting rod 58, which is located between the separate pairs 59 of bell cranks 54 and 57, and said rod is pivoted to the bell cranks 57 as shown at 59 and to the bell cranks 54 as shown at 59^a. The bell cranks 54 and 57 are each composed of two halves, as clearly shown in Fig. 17 to facilitate the assemblage of the various parts, it being understood that only one set of the bell cranks are shown in Fig. 17. Pivoted to the bell cranks 54 and 57 at 60 and 61 are fork-shaped members 62 and 63 shown in detail in Fig. 17 and with which are connected turn-buckles 64 and 65 pivoted to a rear die supporting member or holder 66 as shown at 67, and two of the turn-buckles 64 and 65 and the parts connected therewith are employed.

The operation of this mechanism will be readily understood on a consideration of Figs. 11 to 13 inclusive, in which it will be noted that in one complete cycle or rotation of the cams 26, the connecting levers 52 are moved forwardly and upwardly, and the bell cranks 54 and 57 are correspondingly operated and the rear die supporting member or holder 66 is caused to move forwardly by the yokes and turn-buckles as hereinafter set out.

The rear die supporting member is mounted upon rollers 68 which run upon the tracks 22 and support the weight of said rear die supporting member.

The bell cranks 54 are provided at 60 with eccentric pivot pins 69, and the bell cranks 57 are provided at 61 with eccentric pins 70, and cranks 71 and 72 are secured to the eccentric pins 69 and 70 respectively and are coupled together by connecting rods 73, and these cranks and connecting rods are located between the separate parts of the bell cranks 54 and 57 as well as the yokes 62 and 63.

Mounted transversely of the main frame of the machine is a shaft 74 on which is mounted a bell crank 75 provided with backwardly directed fork-shaped members 76 to which are pivotally connected rods 77, one of which is shown in detail in Fig. 17 of the drawing, and these rods carry or are formed integral with the cranks 71. The bell crank 75 is also provided with another

downwardly directed arm 78 located centrally between the fork-shaped members 76 and with which is pivotally connected a rod 79.

5 The operation of the above described mechanism is clearly illustrated in Figs. 11 to 13 inclusive, and it will be apparent on a consideration of said figures that in the complete cycle of operation the die supporting member or holder 66 is moved forwardly on the frame, and by reason of the eccentric pins 69 and 70 the cranks 71 and 72 will be moved from the position shown in Fig. 12 to that shown in Fig. 13 to hold 15 the separate parts of the die together under pressure, as hereinafter described, and to lock the parts temporarily in such position, and to retain the same in such position until the molten metal has been passed through 20 the discharge nozzle into the die.

In Figs. 15 and 16 we have shown sectional detail views of the mechanism for advancing the supplemental frame and the various parts mounted in connection therewith longitudinally of the main frame with the respective parts of said mechanism in different positions. This mechanism comprises a lever 80 provided with an elongated aperture 81 to permit of its movement upon the cam shaft 25, and this lever is located between the adjacent faces of the cams 27 and is provided with oppositely directed rollers 82 which operate in cam grooves 83 in the abutting faces of said cams. The inner end of the lever 80 is pivoted to a lever 84 which is mounted upon a shaft 85, mounted in suitable bearings 86 in the supplemental frame. An I-bolt 87 is mounted in a yoke 88 mounted to upwardly directed exten- 30 tions 89 on the base or main frame 20, and mounted on the bolt 87 are two nuts 90 adapted to regulate the tension of a spring 91 mounted on said bolt, and the bolt passes through a cross member 92 in the yoke 88 and is held in predetermined position by nuts 93.

As above stated, the mechanism shown in Figs. 15 and 16 is designed to advance the supplemental frame on the main frame and to move the die into contact with the molten metal discharge nozzle and to hold the same in such position under the tension of the spring 91.

The supplemental frame 23 has rigidly connected therewith a stationary die supporting member or holder 94, the connection with said frame being made by four rods 95 upon which the movable die supporting member 66 is movably mounted, and the supporting member 94 is mounted upon rollers 96 which facilitate the movement of said supplemental frame longitudinally of the main frame, as above set out. Mounted in the die supporting member 94 is a hollow nozzle 97 which is adapted to receive the molten

metal discharge nozzle as hereinafter set out, and surrounding the nozzle 97 is a water circulating element 98 through which water is adapted to be circulated for cooling the nozzle 97. In Fig. 7 of the drawing, we have 70 shown supported in connection with the die supporting members 66 and 69, dies 99 and 100 respectively and for the purpose of illustration we have indicated a predetermined contour on the adjacent faces of said dies, 75 and have indicated the molten metal passed thereto.

In Figs. 4, 5, 6 and 7 of the drawing, we have shown enlarged views of the rear or furnace end of the machine, and in said 80 figures we have indicated at 101 a furnace of suitable construction having a combustion or heat chamber 102 in which any suitable heating element or elements may be mounted for the purpose of heating a molten metal part 85 or container 103 in which the molten metal from an outside source is placed to maintain the metal therein at a predetermined level. We also employ a supplemental container 104 which for the purpose of description is 90 called a gooseneck, and this container is clamped in a suitable frame 105 by means of a cap 106 held in position by bolts 107, and the container or gooseneck 104 may be adjusted vertically in the frame 105 by 95 means of a rack 108 secured to one side of the top portion of the container 104 and a pinion 109 mounted upon a shaft 110, which extends through one side of the frame 105 and is provided with a square end shown in 100 Fig. 7, whereby a wrench or suitable tool may be applied for the purpose of adjusting the position of the supplemental container or gooseneck 104.

Upon the top of the furnace is mounted 105 two side frame members 111 in and between which the frame 105 is movably mounted, and the frame members 111 are provided with two cam grooves 112 and 113 in which pivots 114 and 115 respectively are movably 110 mounted, said pivots being mounted in connection with the frame 105. The pivots 114 constitute part of a shaft 116, and this shaft extends through the frame members 111, and mounted in connection therewith are bell 115 cranks 117, one of the arms of each of which are provided with elongated slots 118 in which said shaft operates, and said bell cranks extend through bearings 119 on the frame members 111 and to the other arms 120 of which are pivoted connecting rods 121 having turn-buckles 122. Mounted transversely of the main or base frame 20 of the machine beneath the furnace 101 is a shaft 123, which extends beyond the opposite sides of said frame and arms 124 are clamped thereon, one of which is clearly shown in Fig. 4 of the drawing, and the rods 121 are pivoted to the free ends of said arms. Secured to the shaft 123 within the base 130

- frame 20 is a yoke-shaped arm 125 in connection with which the rod 79 is pivotally mounted, as clearly shown in Fig. 6 of the drawing.
- 5 By means of the bell crank, rod and arm construction above described, the supplemental container 104 may be moved from the position shown in Fig. 6 of the drawing to the position shown in Fig. 7 to bring the
- 10 molten metal discharge nozzle 126 of said container into position to enter the nozzle 97 in the die supporting member 94. The chamber 127 of the container 104 is of trap formation, or is divided by a partition wall
- 15 128 which serves to retain the molten metal within said container, and mounted in connection with the top of the supplemental container is a coupling 129 with which is connected a flexible air supply pipe 130,
- 20 which is coupled to a suitable pipe 131 shown in Fig. 4 of the drawing, which pipe is connected or coupled with a compressed air supply valve device 132 shown in detail section in Fig. 10 of the drawing.
- 25 The valve device 132 forms no direct part of our invention but is shown to illustrate one method of controlling the passage of air under pressure to the container 104. The valve device 132 is provided with a compressed air supply pipe 133, which communicates with the chamber 134 of said valve device, the communication being controlled by an intake valve 135, and mounted in the valve device is an exhaust valve 136 which
- 30 .35 communicates with the chamber 134. Pivotally mounted upon the valve device 132 is a controlling element 137 provided with adjusting screws 138 and 139 adapted to operate in connection with the stems of the
- 35 40 valves 135 and 136 to control the operation thereof, and the element 137 is held in its normal or inoperative position by a spring 140 in which position of said element the exhaust valve 136 is depressed, and pivoted
- 45 to the element 137 is an operating rod 141 which is adapted to be actuated by an automatic valve tripping mechanism 142 shown diagrammatically in Fig. 14 of the drawing to move the element 137 into the position
- 50 shown in Fig. 10 to open the intake valve 135. The exhaust valve is employed to relieve the air pressure in the pipes leading to the container 104 as well as the air pressure in said container.
- 55 The mechanism 142 shown in detail in Fig. 14 is mounted upon and movable with the supplemental frame and comprises a cam 143 mounted upon the shaft 25 and provided with a projection 144 adapted to operate in connection with a roller 145 on a lever 146 slidably mounted on the shaft 25, said lever being provided with an elongated aperture 147 through which the shaft 25 passes. The free end of said lever is pivoted to a bell crank 148 mounted upon a
- stud 149 secured to the supplemental frame 23, and pivoted to said bell crank is a rod 150, which extends forwardly and passes through a bracket 151 movably mounted in connection with the die supporting member 94, and a spiral spring 152 is mounted upon the rod 150 between the bracket and said supporting member 94 and normally holds the parts of the mechanism 142 in an operative position, and mounted on the front face of the bracket 151 is an adjusting screw 153 which is adapted to strike the end of the rod 141 to operate the element 137 to move the same into the position shown in Fig. 10 of the drawing.
- 60 In Figs. 1 and 2, we have shown ejection rods 154 mounted in connection with hangers 155 on the rods 95 of the supplemental frame. These rods are provided with nuts 154^a adjustable thereon to control the movement of said rods, and said rods are adapted to extend through the member 66 and are secured to plates 156 to which plates are secured supplemental ejector rods 157 which extend into the die proper and are adapted to remove the casting therefrom as shown in Fig. 2 of the drawing. At 158 is shown a hand wheel which is mounted upon the drive shaft 32 which forms a part of the clutch mechanism by means of which the shaft 32 may be rotated by hand, if desired.
- 65 The operation of the machine will be readily understood from the foregoing description when taken in connection with the accompanying drawings and the following statement. The position of the various parts of the machine shown in Fig. 1 are their normal position in which the die supporting members 66 and 94 are in their separated position, and the supplemental frame members 66 and 94 are out of engagement with the furnace 101 and the goose-neck or supplemental container 104 is in the position shown in Fig. 6 of the drawing. If the clutch operating handle 38 be operated to move the clutch 35 into operative position, the cams 26 and 27 will be rotated in the manner hereinbefore set out, and the die supporting member 66 will be moved on the main frame and in the supplemental frame to bring the separate parts 99 and 100 of the dies together and to lock said dies in such position, this operation being accomplished by the lever, bell crank, and rod mechanisms hereinbefore described, after which the supplemental frame, including the members 66 and 94 thereon are moved longitudinally of the main frame, and in the above operation the goose-neck or supplemental container 104 is moved into the position shown in Fig. 7, and at the end of said last named operation the nozzle 97 is moved into engagement with the discharge nozzle 126 and held in firm engagement
- 70 75 80 85 90 95 100 105 110 115 120 125 130

therewith under the tension of the spring 91. When the contact or coupling has been made between the separate nozzles 97 and 126, the air valve device 132 is actuated, or 5 the parts thereof, moved into the position shown in Fig. 10 to admit air under pressure into the container or goose-neck 104 to force the molten metal therefrom into the contour or core of the dies as shown in Fig. 10 7 of the drawing, after which the supplemental frame with the members 66 and 94 are moved backwardly out of engagement with the furnace or the discharge nozzle 126 of the container 104, and as this backward 15 operation continues the dies are separated by the backward movement of the supporting member 66 into the position shown in Fig. 1 in which last operation the casting may be ejected from the die, or one part 20 thereof. In the last named operation, or in the backward movement of the supplemental frame the supplemental container or goose-neck 104 returns to the position shown in Fig. 6 to permit of the refilling of 25 said supplemental container with the molten metal in the main container.

In the above described operation when the lever 38 is operated to move the clutch into operative position the roller 43 is withdrawn 30 from engagement with the groove 42 and the clutch moved into operative position to permit of the starting of the machine, and when the parts of the supplemental frame have returned to their normal position as 35 shown in Fig. 1, the roller 43 will again drop into the groove 42 of the cam 41 to automatically stop the machine, or to move the clutch 35 into inoperative position.

It will be apparent that the lever 38 may 40 be operated at will to move the clutch into operative and inoperative position to stop and start the machine, whenever desired, and it will also be apparent that the cam 41 and the mechanism operating in connection 45 therewith may be eliminated so that when the machine is once put in operation it will continuos to operate until the clutch is manually moved into position to stop the machine, in other words, the machine may continue to operate automatically in the production of die-castings without any manual control, whatever, except to stop and start the machine for examinations, repairs and the like.

50 It will be apparent on a consideration of Figs. 11, 12 and 13 of the drawing that the die supporting member 66 is moved forwardly into engagement with the die supporting member 94 by the operation of the bell cranks, levers and the like from the position shown in Fig. 11 to that shown in Fig. 12, and said die supporting members 66 and 94 are locked together by a slight additional movement of the cranks 71 and 55 72 from the position shown in Fig. 12 to

that shown in Fig. 13 thus preventing the separation of the dies in the die supporting members 66 and 94 in the operation of forcing molten metal thereinto under pressure.

70 In the several views of the drawing, it will be noted that certain details of the construction are omitted, broken away or the like in order to simplify the illustration of the mechanisms or operative parts of the machine shown in the separate figures, and while we have shown and described certain details of construction for carrying our invention into effect, it will be understood that we are not necessarily limited to the details 75 of construction herein shown and described, and various changes therein and modifications thereof may be made, within the scope of the appended claims, without departing from the spirit of my invention or sacrificing its advantages.

80 Having fully described our invention, what we claim as new and desire to secure by Letters Patent, is:—

85 1. In a die-casting machine, an automatically operated molten metal discharge element, an automatically operated die holder and carrier movable toward and from said discharge element, and said holder being composed of separate parts movable toward and from each other and to which the separate parts of the die are adapted to be secured in the movement thereof toward and from said element.

90 2. In a die-casting machine, an automatically operated molten metal discharge element, an automatically operated die holder and carrier movable toward and from said discharge element, said holder being composed of separate parts movable toward and from each other and to which the separate parts of the die are adapted to be secured in the movement thereof toward and from said element, and means for holding said 95 die parts together.

100 3. In a die-casting machine, an automatically operated molten metal discharge element, an automatically operated die holder and carrier movable toward and from said discharge element, said holder being composed of separate parts movable toward and from each other and to which the separate parts of the die are adapted to be secured in the movement thereof toward and from said element, means for holding said die 105 parts together, and means for controlling the operation of said holder and carrier and the separate parts thereof.

115 4. In a die-casting machine, an automatically operated molten metal discharge element, an automatically operated die holder and carrier movable toward and from said discharge element, said holder being composed of separate parts movable toward and from each other and to which the separate 120 parts of the die are adapted to be secured in the movement thereof toward and from said element, means for holding said die parts together, and means for controlling the operation of said holder and carrier and the separate parts thereof.

125 5. In a die-casting machine, an automatically operated molten metal discharge element, an automatically operated die holder and carrier movable toward and from said discharge element, said holder being composed of separate parts movable toward and from each other and to which the separate 130 parts of the die are adapted to be secured in the movement thereof toward and from said element, means for holding said die parts together, and means for controlling the operation of said holder and carrier and the separate parts thereof.

parts of the die are adapted to be secured in the movement thereof toward and from said element, means for holding said die parts together, and automatically operated 5 means for forcing molten metal from said element into a die mounted in said holder and carrier.

5. In a die-casting machine, an automatically operated molten metal discharge element, and an automatically operated die 10 holder and carrier the die supporting member of which is movable toward and from said element through a lever mechanism which is adapted to hold a complete die 15 mounted in said holder and carrier in firm engagement with said discharge element.

6. In a die-casting machine, an automatically operated molten metal discharge element, an automatically operated die holder 20 and carrier the die supporting member of which is movable toward and from said element through a lever mechanism which is adapted to hold a complete die mounted in said holder and carrier in firm engagement 25 with said discharge element, and means for controlling the operation of said holder and carrier.

7. In a die-casting machine of the class described, a main molten metal container, 30 a supplemental goose-neck container movably mounted in said main container and provided at its free discharge end with a detachable nozzle, means whereby compressed air may be passed into the supplemental container for discharging molten metal through the discharge nozzle there- 35 of, means for operating said supplemental container, and means for adjusting the position of said supplemental container in its 40 support.

8. In a die-casting machine of the class described, a die holder and carrier mechanism movably mounted on said machine, said mechanism comprising die supporting 45 members movable toward and from each other, means for automatically moving said members together, and means for moving said mechanism on said machine.

9. In a die-casting machine of the class 50 described, a main frame, a supplemental frame movably mounted on the main frame, die supporting members on said supplemental frame and one of which is movable toward and from the other in the movement 55 of the supplemental element, and means involving cam members for automatically operating said members.

10. In a die-casting machine of the class 60 described, a main frame, a supplemental frame movably mounted on the main frame, die supporting members on said supplemental frame and one of which is movable toward and from the other in the movement 65 of the supplemental element, means involving cam members for automatically

operating said members, and other means involving cams for automatically moving said supplemental frame on the main frame.

11. In a die-casting machine of the class described, a main frame, a supplemental frame movably mounted on the main frame, die supporting members on said supplemental frame, and one of which is movable toward and from the other, means involving 70 cam members for automatically operating said members, other means involving cams for automatically moving said supplemental frame on the main frame, and means involving levers for retaining said supporting members in a predetermined position. 75

12. In a die-casting machine of the class described, a main frame, a supplemental frame movably mounted on the main frame, die supporting members on said supplemental frame, and one of which is movable 80 toward and from the other, means involving cam members for automatically operating said members, other means involving cams for automatically moving said supplemental frame on the main frame, means involving 85 levers for retaining said supporting members in a predetermined position, and a clutch device for controlling the operation 90 of said supplemental frame.

13. In a die-casting machine of the class described, a main frame, a supplemental frame movably mounted on the main frame, die supporting members on said supplemental frame and one of which is movable toward and from the other, means involving 95 cam members for automatically operating said members, other means involving cams for automatically moving said supplemental frame on the main frame, means involving levers for retaining said supporting members in a predetermined position, and a clutch device for controlling the operation 100 of said supplemental frame and the die supporting members thereof. 105

14. A die-casting machine, comprising a main frame, a furnace at one end thereof, a molten metal container in said furnace, a discharge element in said container, a supplemental frame movable longitudinally of the main frame and toward and from 115 said furnace, said supplemental frame being provided with die supporting members adapted to receive and support suitable dies, and said discharge element being provided with a nozzle in connection with which 120 the dies are adapted to operate.

15. A die-casting machine, comprising a main frame, a furnace at one end thereof, a molten metal container in said furnace, a discharge element in said container, a supplemental frame movable longitudinally 125 of the main frame and toward and from said furnace, said supplemental frame being provided with die supporting members adapted to receive and support suitable dies, 130

- 5 said discharge element being provided with a nozzle in connection with which the dies are adapted to operate, means for automatically operating said supplemental frame to move the same and the die supporting members thereof toward and from said furnace, and means for automatically moving said discharge element into operative position. 70
- 10 16. A die-casting machine comprising a main frame, a furnace at one end thereof, a molten metal container in said furnace, a discharge element in said container, a supplemental frame movable longitudinally of the main frame and toward and from said furnace, said supplemental frame being provided with die supporting members adapted to receive and support suitable dies, said discharge element being provided with a nozzle in connection with which the dies are adapted to operate, means for automatically operating said supplemental frame to move the same and the die supporting members thereof toward and from said furnace, means for automatically moving said discharge element into operative position, and means for automatically passing compressed air into said discharge element to discharge the molten metal therefrom. 80
- 15 17. In a die-casting machine of the class described, die supporting members movably mounted in said machine and one of which is movable toward and from the other in the movement of said members, and means for operating said last named member and for firmly holding dies mounted therein and in said other member in engagement with each other. 85
- 20 18. In an automatically operated die-casting machine of the class described provided with a molten metal discharge element, means for moving a suitable die toward and from said element, means for moving said element into operative and inoperative positions, said first-named means being composed of separate parts, and means for holding the separate parts of a die together therein and for locking the same against separation. 90
- 25 19. In an automatically operated die-casting machine of the class described provided with a molten metal discharge element, means for moving a suitable die toward and from said element, means for moving said element into operative and inoperative positions, said first-named means being composed of separate parts, means for holding the separate parts of a die together therein and for locking the same against separation, means for separating said die parts, means for ejecting the casting from one part of said die when said die parts are separated, and means for manually controlling the operation of the machine. 95
- 30 20. In an automatically operated die-casting machine of the class described provided with a molten metal discharge element, means for moving a suitable die toward and from said element, means for moving said element into operative and inoperative positions, said first-named means being composed of separate parts, means for holding the separate parts of a die together therein and for locking the same against separation, means for separating said die parts, means for ejecting the casting from one part of said die when said die parts are separated, means for manually controlling the operation of the machine, and means for automatically stopping the machine. 100
- 35 21. In an automatically operated die-casting machine of the class described provided with a molten metal discharge element, means for moving a suitable die toward and from said element, means for moving said element into operative and inoperative positions, said first-named means being composed of separate parts, means for holding the separate parts of a die together therein and for locking the same against separation, means for separating said die parts, means for ejecting the casting from one part of said die when said die parts are separated, and means for manually controlling the operation of the machine. 105
- 40 22. In an automatically operated die-casting machine of the class described provided with a molten metal discharge element, means for moving a suitable die toward and from said element, means for moving said element into operative and inoperative positions, said first-named means being composed of separate parts, means for holding the separate parts of a die together therein and for locking the same against separation, means for separating said die parts, means for ejecting the casting from one part of said die when said die parts are separated, means for manually controlling the operation of the machine, and means for automatically stopping the machine. 110
- 45 23. A die-casting machine comprising automatically operated die supporting members movable toward and from each other, an automatically operated molten metal discharge element in connection with which a die supported in said members is adapted to operate, automatically operated means for forcing molten metal from said element into said die, and means involving a tensile device for holding said die in firm engagement with said element. 115
- 50 24. A die-casting machine of the class described comprising a main frame, a supplemental frame automatically movable on the main frame, an automatically operated molten metal discharge element, means on said supplemental frame for supporting the separate parts of a die thereon whereby in the movement of said supplemental frame said die may be moved into and out of engagement with said element, and automatically operated means for moving the separate parts of the die toward and from each other. 120
- 55 25. A die-casting machine of the class de- 125
- 60
- 65

- scribed comprising a main frame, a supplemental frame automatically movable on the main frame, an automatically operated molten metal discharge element, means on 5 said supplemental frame for supporting the separate parts of a die thereon whereby in the movement of said supplemental frame said die may be moved into and out of engagement with said element, automatically operated means for moving the separate parts of the die toward and from each other, and means for locking the separate parts of the die together in the operation of passing molten metal thereinto.
- 15 26. A die-casting machine of the class described comprising a main frame, a supplemental frame automatically movable on the main frame, an automatically operated molten metal discharge element, means on 20 said supplemental frame for supporting the separate parts of a die thereon whereby in the movement of said supplemental frame said die may be moved into and out of engagement with said element, automatically operated means for moving the separate parts of the die toward and from each other, means for locking the separate parts of the die together in the operation of passing molten metal thereinto, and means for au- 25 tomatically ejecting the casting from one part of the die when said parts are sepa-rated.
- 30 27. A die-casting machine of the class described comprising a main frame, a sup-35 plemental frame automatically movable on the main frame, an automatically operated molten metal discharge element, means on said supplemental frame for supporting the separate parts of a die thereon whereby in 40 the movement of said supplemental frame said die may be moved into and out of engagement with said element, automatically operated means for moving the sepa-rate parts of the die toward and from each other, means for locking the separate parts of the die together in the operation of passing molten metal thereinto, and automatically operated means for forcing molten metal from 45 said element into said die.
- 50 28. A die-casting machine of the class described comprising a main frame, a sup-55 plemental frame automatically movable on the main frame, an automatically operated molten metal discharge element, means on said supplemental frame for supporting the separate parts of a die thereon whereby in 60 the movement of said supplemental frame said die may be moved into and out of engagement with said element, automatically operated means for moving the separate parts of the die toward and from each other, means for locking the separate parts of the die together in the operation of passing molten metal thereinto, automatically operated means for forcing molten metal

from said element into said die, and means for automatically ejecting the casting from one part of the die when said parts are separated.

29. A die-casting machine of the class de-scribed comprising a main frame, a sup-70 plemental frame automatically movable on the main frame, an automatically operated molten metal discharge element, means on said supplemental frame for supporting the sep-75 arate parts of a die thereon whereby in the movement of said supplemental frame said die may be moved into and out of en-gagement with said element, automatically operated means for moving the separate 80 parts of the die toward and from each other, means for locking the separate parts of the die together in the operation of passing molten metal thereinto, automatically operated means for forcing molten metal from 85 said element into said die, means for automatically ejecting the casting from one part of the die when said parts are separated, and manually operated means for control-ing the operation of the machine. 90

30. A die-casting machine of the class de-scribed comprising a main frame, a sup-95 plemental frame automatically movable on the main frame, an automatically operated molten metal discharge element, means on 100 said supplemental frame for supporting the separate parts of a die thereon whereby in the movement in said supplemental frame said die may be moved into and out of en-gagement with said element, automatically 105 operated means for moving the separate parts of the die toward and from each other, means for locking the separate parts of the die together in the operation of passing molten metal thereinto, automatically op-110 erated means for forcing molten metal from said element into said die, means for automatically ejecting the casting from one part of the die when said parts are separated, manually operated means for controlling the 115 operation of the machine, and means for automatically stopping the machine.

31. A machine for automatically produc-ing die-castings from heated metal comprising a metal discharge element, a die 115 holder and carrier movable into and out of engagement with said element, whereby the molten metal of said element may be passed into a suitable die mounted in said holder and carrier, means for fore-ing the metal from said element into said die, means for retaining the separate parts of the die in firm contact in the operation of passing metal thereinto, and means for sepa-rating the die parts and for automatically 120 ejecting the casting formed thereby from one of said die parts.

32. A die-casting machine of the class de-scribed comprising a main frame pro-125 vided at one end with a furnace having a 130

toward and from the other, and one of said parts being provided with a nozzle adapted to cooperate with the discharge nozzle of said supplemental container, means for operating said supplemental frame and said supplemental container to bring said nozzles together to permit of the passage of molten metal from said supplemental container into a suitable die supported in said holder and carrier, means for automatically operating said compressed air supply means to said supplemental container, means for holding the separate parts of said holder and carrier of the die supported therein in firm contact in the operation of passing metal into said die in the formation of a casting, means for ejecting the casting so formed from the die or one part thereof when the separate parts of the holder and carrier are separated, and means for controlling the operation of the machine or the various parts thereof.

37. In a die-casting machine of the class described provided with a molten metal discharge element, a die holder and carrier movable toward and from said element in a predetermined path, said die holder and carrier comprising independent die supporting members movable toward and from each other in the same path as the movement of said holder and carrier.

38. In a die-casting machine of the class described provided with a molten metal discharge element, a die holder and carrier movable toward and from said element in a predetermined path, said die holder and carrier comprising independent die supporting members movable toward and from each other in the same path as the movement of said holder and carrier, and independent means for actuating the separate die supporting members whereby one of said members is moved toward and from the other and said members collectively moved toward and from said discharge element.

39. In a die-casting machine of the class described provided with a molten metal discharge element, a die holder and carrier movable toward and from said element in a predetermined path, said die holder and carrier comprising independent die supporting members movable toward and from each other in the same path as the movement of said holder and carrier, independent means for actuating the separate die supporting members whereby one of said members is moved toward and from the other and said members collectively moved toward and from said discharge element, and means for tensionally holding said holder and carrier or the separate die supporting members thereof in firm engagement with said element.

40. In a die-casting machine of the class

described a main frame, a molten metal discharge element movably mounted in connection with one end portion of the main frame, a supplemental frame mounted to move longitudinally of the main frame and toward and from said element, said supplemental frame being provided with die supporting members, one of which is movable with the supplemental frame and the other of which is movable relatively to the first named member, and the movement of said last named die supporting member being in the same plane as the movement of said supplemental frame.

41. In a die-casting machine of the class described a main frame, a molten metal discharge element movably mounted in connection with one end portion of the main frame, a supplemental frame mounted to move longitudinally of the main frame and toward and from said element, said supplemental frame being provided with die supporting members, one of which is movable with the supplemental frame and the other of which is movable relatively to the first named member, the movement of said last named die supporting member being in the same plane as the movement of said supplemental frame, and means involving levers for actuating the supplemental frame and the movable die supporting member mounted therein.

42. In a die-casting machine, die-supporting members, and automatically actuated means for producing relative movement between all of said members in a predetermined path and into predetermined position in the machine in the same path.

43. In a die-casting machine, a molten metal containing device, a die-holding device comprising die-holding parts, means for producing relative movement between all of said parts in a path of given direction, and one of said devices being automatically movable in said driven directional path into and out of operative relation to the other.

44. In a die-casting machine, a molten metal containing device, a die-holding device comprising die-holding parts, automatic means for producing relative movement between all of said parts in a path of given direction, and one of said devices being automatically movable in said given directional path into and out of operative relation to the other.

45. In a die-casting machine, a molten metal containing device, a die-holding device comprising die-holding parts, automatic means for producing rectilinear movement between all of said parts and one of said devices being movable in said rectilinear path into and out of operative relation to the other.

46. In a die-casting machine, die supporting members, automatic means for produc-

ing relative movement between all of said members, and automatically operated means for locking dies supported in said members momentarily against separation in the operation of passing molten metal thereinto.

47. In a die-casting machine employing a movable carriage, actuated means carried by said carriage for operating mechanism thereof and of the machine.

48. In a die-casting machine, a movable carriage, power driven means carried by said carriage and adapted to actuate the same and the several operative parts thereof and of the machine.

49. In a die-casting machine, a movable carriage, relatively movable die supporting members on said carriage and a driven member carried by said carriage and adapted to actuate said carriage and the die supporting members thereof.

50. In a die-casting machine, a molten metal container, a movable carriage, relatively movable die supporting members on said carriage, a driven member carried by said carriage and adapted to actuate said carriage and the die-supporting members thereof to move dies supported in said members into engagement with said molten metal container and to automatically discharge molten metal from said container into said dies.

51. In a die-casting machine, a reciprocating die-supporting and operating carriage, a belt-driven pulley carried by said carriage and by means of which said carriage and the mechanism thereof is actuated.

52. In a die-casting machine, a molten

metal discharge element, relatively movable die-supporting members movable into and out of engagement with said element, and a reciprocating power driven element movably disposed on the machine and adapted to automatically actuate the several mechanisms of the machine.

53. In a die-casting machine, a molten metal discharge element, relatively movable die-supporting members movable into and out of engagement with said element, a power driven element movably disposed on the machine and adapted to automatically actuate the several mechanisms of the machine, and means operated by said power driven element for automatically stopping the machine.

54. A machine for automatically producing die-castings from heated metal comprising a metal discharge element, a reciprocating die holder and carrier movable into and out of engagement with said element whereby the molten metal of said element may be passed into a suitable die mounted in said holder and carrier, means for forcing molten metal from said element into said die, means for retaining the separate parts of the die in locked relation and in firm contact with said element in the operation of passing molten metal thereinto, and means for separating the die parts after the casting has been formed.

In testimony that we claim the foregoing as our invention we have signed our names this 8th day of February 1922.

JOSEPH SOSS.
LOUIS H. MORIN.
